PACKING TOOL FOR FORMING AND INSTALLING IMPRESSIONABLE COMMUNICATED OR PLASTIC PACKING

Earl E. Brown, Camden, N. J., assignor of one-half to George A. Streitz, Camden, N. J.

Application February 3, 1948; Serial No. 6,026

4 Claims. (Cl. 18—34)

1

This invention relates to improvements in a packing tool for forming and installing impressionable comminuted or plastic packing.

The primary object of this invention is the provision of improved means to apply impressionable packing material within packing boxes and around shafts with accuracy and facility.

A further object of this invention is the provision of an improved tool assemblage for the formation of packing material.

A further object of this invention is the provision of improved impressionable packing rings.

Other objects and advantages of this invention will be apparent during the course of the following detailed description.

In the accompanying drawings, forming a part of this specification, and wherein similar reference characters designate corresponding parts throughout the several views—

Figure 1 is a perspective view showing the improved tool assemblage with packing ring segments formed therein.

Figure 2 is a perspective view showing how the complementary packing ring segments are shaped.

Figure 3 is a cross-sectional view showing the type of packing box for which the improved packing is best adapted.

Figure 4 is a plan view of a mold assemblage used in forming the packing.

Figure 5 is a cross-sectional view taken thru the tool structure substantially on the line 5—5 of Figure 7.

Figure 6 is a vertical cross-sectional view taken thru the packing tool showing a packing dividing plunger in raised position; the view being taken substantially on the line 6—6 of Figure 4.

Figure 7 is a view of the parts shown in Figure 6 but with the plunger structure in a lowered position.

Figure 8 is a cross-sectional view taken substantially on the line 8—8 of Figure 4.

Figure 9 is a plan view showing a plier-like packing holding and forming tool.

Figure 10 is a side elevation of the tool shown in Figure 9, with one segmental packing forming jaw partially removed.

In the drawings, wherein for the purpose of illustration is shown only a preferred embodiment of the invention, the letter A may generally designate the tool assemblage. It includes a mold casing structure B formed of a lower part C and upper part D. A packing dividing plunger E is associated with the mold casing structure B. An improved packing holding tool F is provided.

as part of the assemblage A for cooperation with the mold casing structure and packing dividing plunger.

In general, it is a purpose of the invention to provide an impressionable packing material formed in the tool assemblage A and held or supported upon the packing holding tool in complementary segments, so the latter can be applied with facility about a shaft and within a packing box. The material of which the packing is formed may be pliable, comminuted or flexible.

Referring to the mold casing structure B, the lower part C is of cup-shaped formation including cylindrical portion 10 which flares outwardly and downwardly at 11 and is provided with enclosing bottom wall 12. This provides an upwardly opening compartment 13 which is adapted to receive therein a cylindrical body portion 14 of the upper part D. The latter includes the cylindrical body portion 14 having integral therewith a mold portion 15 of circular shape defining a compartment 16 adapted to receive the jaw segments of the packing holding tool F, as will be subsequently described. The passageway 20 within the cylindrical part 14 slidably receives the packing dividing plunger arrangement E shown in the drawings. The parts C and D are held together by a set screw 10a.

Generally, it is the purpose of the packing dividing plunger to provide a central mold core about which the packing is formed and to also provide dividing wings or flanges for the shaping of the packing into complementary segments. To that end the packing dividing plunger structure E consists of the semi-cylindrical sections 30 and 31 which at their upper ends, when in complementary assemblage, have secured therebetween a shim 32, as by rivets or pins 33 radially extended thru the sections 30 and 31 and the shim, as shown in Figure 8. The shim 32 projects radially beyond the plunger body to provide packing dividing and forming wings or flanges 32a and 32b. A second shim 35 is provided as a spacer at the lower end of the plunger and located between the sections 30 and 31 thereof and secured in place by a pin 36. The plunger E reciprocates within the passageway 20 so that its upper core providing end and the wings 32a and 32b may be extended and retracted with respect to the compartment 16 of the mold part 15. A stop collar 40 is secured to the lower end of the plunger E as by means of a set screw or other expedient 41, shown in Figure 6. The purpose of this collar is to limit the upward extension of the plunger so as to accurately position

the packing forming portions thereof within the mold compartment 16.

A countersunk opening 50 is provided in the lower end of the plunger adapted to receive the upper end of a compression spring 51 which is seated upon a centering screw 52 detachably located in the bottom wall 12 of the casing structure; the spring normally urging the plunger to the "up" position shown in Figure 8.

The packing holding tool forms part of the mold structure for the packing material. It consists of plier-like lever portions 60 and 61 pivoted at 62, and having handle portions 60^a and 61^a respectively. The levers 60 and 61 are each laterally offset at 62^a, shown in Figure 10 at their forward ends, and provided with forwardly projecting portions 63 respectively supporting complementary mold segments or heads 64 and 65 each of which is a true half circle. A spring 67 normally urges the segments 64 and 65 apart to the position shown in Figure 9. It is to be noted that the portions 63 are connected close to the ends of the segments so that the portions 63 lie quite close together when the packing holding tool F is closed within the mold end of the assemblage, as shown in Figure 1. When the end edges 70 of the segments are in surface contact, the inner peripheral surfaces 64^a and 65^a of segments 64 and 65 form a true circle. It is upon these peripheries 64^a and 65^a that the packing segments are formed, and to maintain the impressionable material in place after the packing segments have been formed, depressions, serrations or other indentations 71 may be provided inwardly of the peripheral surfaces 64^a and 65^a.

The packing segment receiving portion 15 of the casing structure is cut out at 80 for the purpose of receiving the supporting extensions 63 of the packing hold tool F, as shown in Figure 1. The compartment 16 is of such diameter as to snugly receive the packing forming and supporting segments 64 and 65 and to hold them spaced at their end surfaces 70 to permit the snug sliding of the dividing wings or flanges 32^a and 32^b therebetween, as shown in Figure 1. It is to be noted that the plunger is operated by means of a lever 90 pivoted upon a pin 91 secured in the cylindrical portion 14 of the part D. The inner end of the lever 90 is provided with a disc-shaped head 92 which operates slidably within a passage-way 94 formed or cut out in the facing surfaces of the plunger segments 30 and 31, as shown in Figures 6, 7 and 8 of the drawings. A handle end of the operating lever extends thru a suitable recess 97 in the casing portion C. Movement of lever 90 slides the plunger to the extended or retracted positions. In the downmost position, shown in Figure 7, the shim wings lie flush with the floor surface 100 of the compartment 16. The top edges of the jaw segments lie flush with the top edge of the mold part 15 of the casing structure and the lower edges of the jaw segments rest upon the floor 100.

Referring to Figure 4, it is to be noted that the plunger parts 30 and 31 are each a true half cylinder so that with the shim 32 therebetween the outer packing forming convex surfaces 30^a and 31^a are struck from two different centers designated at 30^b and 31^b in Figure 4 of the drawings. It was before mentioned that each segment 64 and 65 is a true half circle, so that when in the position shown in Figure 1, complete half segments (180°) of packing can be formed.

as indicated at 110 and 111, in Figures 1 and 2 of the drawings.

With reference to the mode of forming the packing G, the plunger E is retracted as shown in Figure 7. The operator, thru the handles 60 and 60^a, moves the jaw segments together until the ends 70 abut. In this position the ring formed by the segments will readily enter the compartment 16 of the casing structure and upon release of the handle the jaw segments will open to assume the position shown in Figure 1. The operator by pressing the lever 90 now moves the plunger and shim wings up into the position shown in Figure 1. The packing molding surfaces consist of both sides of the wings 32^a and 32^b; the floor surface 100; the inner segmental surfaces of the segments 64 and 65, and the external convex surfaces 30^a and 31^a of the plunger segments. The operator, with his fingers or a tamp of the same shape as the compound rings shown in Figure 2, now forces the impressionable packing material into the semi-circular cavities provided in the mold thereof and levels it off flush with the top surfaces of the plunger, shim and jaw segments, as indicated in Figure 1. Of course the material is forcefully pressed into the mold cavities. Form the position in Figure 1, the packing holding tool F may be lifted after retraction of the plunger and the shim, by slight contraction of the jaw segments. The packing segments 110 and 111 will adhere to the packing forming or mold segments 64 and 65 of the tool F, since it has been forced into the depressions 71. With the packing thus held in the mold segments of the tool F, the operator may permit the levers of the tool to open as wide as necessary to enable the packing segments 110 and 111 to be positioned over the shaft 115, shown in Figure 3, at the outer end of the packing box 116. The ring segments may be extruded without mutilation from the tool segments 64 and 65 into the packing box compartment 117, by means of the portion 118^a of the slidable packing gland 118. As many of the packing segments (in their complementary ring formation) as necessary, may be placed in the packing box. The packing box structure of Figure 3 is shown as incidental to the invention. Of course the gland collar 118^a is of less external diameter than the internal diameter of the ring formed by the tool segments 64 and 65 when they are closed, the difference in dimensioning being .010". The thickness of the shim 32 is .022".

It is preferred to form the tool parts of stainless steel, altho the material is relatively unimportant except when it is used around acid materials.

Various changes in the shape, size and arrangement of parts and variation in the steps of the method of forming the packing may be made without departing from the spirit of the invention or the scope of the claims.

I claim:

1. In a device⁶ for the forming of ring-shaped packing of impressionable material the combination of a plier-like tool comprising relatively pivoted lever portions having at the ends thereof mold heads each provided with a true 180° semi-circular socket therein, the levers when moved together holding said heads in a true 360° circle providing socket, a supporting casing having a compartment therein associated and arranged to receive the heads of the tool so that they will be relatively spaced just slightly out of true circle providing position, said casing compartment hav-

ing a bottom moulding wall complementary to the semi-circular sockets of said tool heads, and means movably carried by said casing including a thin packing dividing structure which moves into and out of the said compartment in the space between said heads.

2. In a device for the formation of segmental-shaped packings the combination of a plier-like packing forming tool comprising a pair of pivotally connected lever portions and heads thereon each defining a semi-circular socket adapted to receive therein an impressionable material, a casing having a compartment therein opened upwardly and provided with a moulding wall in the bottom thereof, said casing compartment being adapted to receive therein the heads of said levers to hold said heads in a relatively spaced relation just slightly out of the true circular position with the edges of said heads abutting said moulding wall and the moulding wall being disposed in complementary relation to the sockets of said heads to cooperate in the formation of the packing segments, a core reciprocably carried by said casing for axial movement thru said compartment and into the sockets of the packing forming heads, and packing dividing wings carried by said core and movable therewith for entering said compartment and sockets with the core to cooperate with said heads in the complementary formation of true semi-circular packing segments.

3. In a device for the formation of segmental-shaped packings the combination of a plier-like packing forming tool comprising a pair of pivotally connected lever portions and heads thereon each defining a semi-circular socket adapted to receive therein an impressionable material, a casing having a compartment therein opened upwardly and provided with a moulding wall in the bottom thereof, said casing compartment being adapted to receive therein the heads of said levers to hold said heads in a relatively spaced relation just slightly out of true circular position with the edges of said heads abutting said moulding wall and being disposed in complementary relation to the sockets of the heads for the formation of the packing segments, a core reciprocably carried by said casing for axial movement thru said compartment and into the sockets of the packing forming heads, packing dividing wings carried by said core and movable therewith for entering said compartment and sockets with the core to coop-

erate with said heads in the complementary formation of true semi-circular packing segments, a spring carried by said casing normally forcing said core and the wings thereof into said compartment and sockets, and lever means carried by the casing for moving the core into projected or retracted relation with respect to said compartment and sockets.

4. In a device for the formation of segmental-shaped packings the combination of a pair of segmental-shaped packing receiving heads each defining a semi-circular socket adapted to receive therein an impressionable material, means connecting said heads so that they may move towards and away from each other, a casing having a compartment therein opening upwardly and provided with a moulding wall in the bottom thereof, said casing compartment being adapted to receive therein the said head segments to hold them in spaced relation just slightly out of true circular position with the bottom edges of said heads abutting said moulding wall and the moulding wall being disposed in complementary relation to the sockets of said heads to cooperate in the formation of packing segments, a core reciprocably carried by said casing for axial movement thru said compartment and into the sockets of said packing forming segmental heads, and packing dividing wings carried by said core and movable therewith for entering said compartment and sockets with the core to cooperate with said heads in the complementary formation of true semi-circular packing segments.
